(57) CLAIM

The ornamental design for an auto-injector, as shown and described.

DESCRIPTION

FIG. 1 is a front right perspective view of an auto-injector in a capped configuration showing our new design;

FIG. 2 is a front elevation view thereof;
FIG. 3 is a rear elevation view thereof;
FIG. 4 is a left side view thereof;
FIG. 5 is a right side view thereof;
FIG. 6 is a top plan view thereof;
FIG. 7 is a bottom view thereof;
FIG. 8 is a front right perspective view of a cap of the auto-injector in an uncapped configuration showing our new design;
FIG. 9 is a front elevation view of FIG. 8;
FIG. 10 is a rear elevation view of FIG. 8;
FIG. 11 is a left side view of FIG. 8;
FIG. 12 is a right side view of FIG. 8;
FIG. 13 is a top view of FIG. 8;
FIG. 14 is a bottom view of FIG. 8;
FIG. 15 is a front right perspective view of a body of the auto-injector in an uncapped configuration showing our new design;
FIG. 16 is a front elevation view of FIG. 15;
FIG. 17 is a rear elevation view of FIG. 15;
FIG. 18 is a left side view of FIG. 15;
FIG. 19 is a right side view of FIG. 15;
FIG. 20 is a top view of FIG. 15; and,
FIG. 21 is a bottom view of FIG. 15.
The broken lines of even length shown in the drawings illustrate portions of the auto-injector that form no part of the claimed design. The broken lines of uneven length define the boundaries of the claimed design.
